FOLDING MACHINE

Wayne E. Myers, Benton Harbor, Mich., assignor
to St. Joe Machines, Inc., St. Joseph, Mich., a
corporation of Michigan

Application June 12, 1939, Serial No. 278,603

34 Claims. (Cl. 270—81)

This invention relates to a folding machine and to control mechanisms for measuring articles.

It is an object of this invention to provide a folding machine specifically for folding laundry flatwork which, as compared to prior machines of this character, is relatively simple in construction, efficient and accurate in operation, and inexpensive to maintain.

Machines have previously been proposed for folding flat-work laundry articles, but such machines in substantially all cases, embody complex timing mechanisms which must at all times be maintained in synchronism with each other and with the movement of the article-conveying means. The cost of maintaining such mechanisms and means in proper synchronism to fold such articles satisfactorily has been so high that it has oftentimes been found more economical to fold such articles by hand. It has also been previously proposed to control such folding machines by various forms of levers or switches engaging the forward and rear edges of the article to determine the operation of the timing mechanisms, but inasmuch as the articles to be folded are highly flexible, their use as operating elements for the levers or switches has not been satisfactory, and the operation of these levers or switches has not been certain. In order to overcome this difficulty and insure the certainty of operation of these levers or switches, others have suggested the use of conveying belts engaging both sides of the flexible article so as to maintain it taut and, in effect, decrease its flexibility. However, such duplicate sets of tapes not only increase the cost and complexity of the machine, but also apply stresses in some cases greater than the article can withstand, resulting, therefore, in the tearing or destruction of the article. Furthermore, such levers or switches as have been heretofore used present the ever-present danger of engagement in a slit or with a thread of the article and thus, as the article is moved past them, tear or otherwise injure the article.

It is, accordingly, therefore an important object of applicant's invention to provide in a folding machine a control mechanism that is responsive to the presence of an article or sheet to be folded but which eliminates these defects and insufficiencies of the prior devices and does not include any means or mechanism which physically engages the article to effect the control function and which at the same time is rugged in construction and inexpensive to maintain in proper working condition.

A more specific object of applicant's invention

is to provide in a folding machine or the like photo-electric measuring means or mechanisms by which the folding means or the like may be accurately controlled to fold or subdivide the article along the lines of fold predetermined in accordance with the measured lengths of the articles.

Applicant's invention further contemplates the provision of a novel photo-electric measuring means, device, or system to exert a controlling function determined by a dimension of the article measured.

Another object of applicant's invention is to provide an automatic folding machine capable of folding articles one after another in rapid succession irrespective of their relative sizes; capable of simultaneously handling or folding a plurality of small sheets by separate folding instrumentalities or blades or a single large sheet by the same folding instrumentalities or blades and capable of folding each article a plurality of times along lines of fold accurately positioned with respect to the edges of the articles in accordance with the dimensions of the articles.

25 A further object of the invention is to provide an automatic friction clutch means for connecting a selected measuring device to a continuously operating driving mechanism which clutch means is positive in operation to cause movement 30 of the device through a given fixed distance upon each operation, yet generates no substantial amount of heat over a long period of continuous use.

Other and further objects and advantages of 35 the invention will be apparent from the following description when taken in connection with the accompanying drawings, wherein

Figure 33 is a schematic circuit diagram of a modified wiring system for the several parts of the machine.

As shown in the drawings, the machine embodying the invention comprises a frame 2 (Fig. 1); an article-conveying means or mechanism 4 (Fig. 2); folding means or mechanism 6 (Fig. 8) for effecting the first fold of an article; folding means or mechanism 8 for effecting the second fold of an article; conveying means or mechanisms 10 and 12 for co-operating with the folding means 6 to effect the first fold of an article, and conveying the once-folded article to the second folding mechanism 8; conveying means or mechanism 14 for co-operating with the conveying means or mechanism 12 and the folding mechanism 8 to effect a second fold of the article and to convey the twice-folded article from the folding mechanism 8 to a point of discharge; measuring means or mechanisms 16 and 18 (Figs. 2 and 10) for controlling the first folding mechanism 6 to effect the first fold of small articles; measuring means or mechanism 20 for control-

ling the first folding mechanism 6 to effect the first fold of a large article; measuring and timing means or mechanisms 22 and 24 (Figs. 5 and 10) for operatively controlling the second folding mechanism 8 to effect a second fold of small articles; measuring means or mechanism 26 (Figs. 2 and 10) operatively controlling the second folding mechanism 8 to effect the second fold for large articles; driving mechanism 28 (Figs. 6 and 10); photoelectric control units 30 and 32 (Figs. 2 and 8) for controlling the operation of the photoelectric measuring means 16 and 18 and also for controlling, if desired, the energization of the light sources for each of the photoelectric measuring means 16, 18, 20, and 26; and a photoelectric controlling unit 34 for controlling the operation of the photoelectric measuring means 20, the photoelectric measuring means 20 in turn controlling the photoelectric measuring means 26.

The frame 2 may comprise parallel side members 36 and transverse frame rods or bars such as shown at 38 in Figure 1. The side frame members 36 may be formed with openings as at 40 forming chambers or housings for the electrical control mechanisms hereinafter to be described, detachable covers 42 being provided to enclose the chambers 40 and the electrical controls contained therein.

30 The article-conveying means or mechanism

The article-conveying means or mechanism 4 comprises as best shown in Figures 1 to 3 a plurality of laterally-spaced feed tapes 44 extending longitudinally of the machine and extending about rollers or drums 46 and 48 carried by transverse shafts 50 and 52 at the forward and rear ends 54 and 56 of the machine, respectively, and journaled in the side frame members 36. The tapes 44 may receive the articles or sheets to be folded from any conventional ironing machine such as shown at 58 in Figure 1, the conveying tapes being driven at a sufficiently greater speed than the conveying mechanism of the ironing machine 58, so that the articles fed to the conveying tapes by the conveying mechanism of the ironing machine will not be rumpled in passage from one to the other and so that even though articles are fed in end-to-end abutting relation along the conveying mechanism of the ironing machine, the articles will be separated by a certain minimum distance by the time they reach the measuring and control units. The rollers or drums 46 and 48 may, if desired, be provided with rings or sleeves (not shown) between adjacent tapes to maintain the tapes in parallel relation.

The machine at its rear end 56 is provided with an article-receiving table or shelf 60 carried by the side members 36 and supports 62.

60 The folding means or mechanisms

The folding means 6 for effecting the first fold of an article comprises, as best shown in Figures 8 and 13, a pair of folding blade sections 64 and 66, each comprising an elongated bar 68 having a plurality of upwardly projecting spaced folding fingers 70 adapted to extend between the tapes in effecting the folding of an article. Each blade section is secured to the outer ends of a plurality of laterally-spaced levers 72 secured to a sleeve 74 journaled on a shaft 76 extending between the side frame members 36. The folding blade sections 64 and 66 are actuated by means of solenoids 78 and 80, respectively, the armature

82 of each solenoid being connected to its respective folding blade section by means of a link 84 pivoted thereto and to a crank or lever 86 secured to the sleeve 14. Upon energization of its respective solenoid, each folding blade section will be moved upwardly from the position shown in solid lines to the position shown in dotted lines in Figure 8 to move the folding fingers upwardly between the feed tapes 44. A channel iron 88, secured to the side members 36, forms a guide or support for the tapes 44 at a point adjacent the folding blade sections 64 and 66 and carries on its upper face a plurality of bevelled article-guiding blocks 90 in laterally-spaced relation and extending between the tapes 44, these blocks 90 causing a transverse hump in each article above the folding fingers of the folding blades to facilitate the folding of the article thereby. The folding blade sections 64 and 66 feed the articles between the conveying means 10 and 12 which co-operate therewith to effect the first fold of each article.

The conveying means 10 comprises a plurality of laterally-spaced tapes 92 passing about rollers or drums 94 and 96 carried by shafts 98 and 100, respectively, extending between and journaled in said frame members 36. The tapes 92 between the rollers 94 and 96 are guided and supported by transverse channel irons 102 and 104, the channel iron 104 also providing a mounting for a bar 106 supporting a plurality of bars 108 extending rearwardly between the tapes 92 and at their rear ends overlying the roller 96, the bars 108 maintaining the tapes 92 in proper spaced relation and extending over the roller 96 in such manner as to prevent the article from adhering to the outer ends of the tapes as they pass downwardly about the roller 96, thereby preventing downward feeding of the articles about this roller.

The conveying means 12 comprises a plurality of feed tapes 110 passing about a forward roller 112 positioned in advance of the roller 94 but lying in the same horizontal plane with the roller 94. The rollers 94 and 112 are positioned in close juxtaposition so that the tapes 92 and 110 effect a sharp line of fold between the articles fed therebetween by the folding blades which are bevelled at their upper ends to pass between the rollers in the spaces between the tapes. The tapes 110 pass about an intermediate roller 114 and a rear roller 116 positioned above the conveying means 14, the roller 116 being provided with rings or annular flanges 118 (Fig. 9) between adjacent tapes to maintain the tapes in proper spaced relation. The rollers 112, 114, and 116 are carried by shafts 120, 122, and 124, respectively, extending between the side members 36, the shafts 120 and 122 being suitably journaled in the side members and the shaft 124 being journaled in bearing blocks or brackets 126, fastened to the upper edges of the side frame members.

The folding means 8 for effecting the second fold of each article comprises folding blade sections 128 and 130 in transverse alignment and similar to the folding blade sections 64 and 66. The folding blade 132 of each of the folding blade sections 128 and 130 is secured to the outer ends of a plurality of levers 134 secured to a sleeve 136 and journaled on a shaft 138 extending between the side frame members 36. The folding blade sections 128 and 130 are actuated by solenoids 140 and 142, respectively, the armature 144 of each solenoid being connected to the sleeve 136

by the link 146 pivotally connected at its opposite ends to the armature and to a lever 147 carried by the sleeve. Means are provided for counter-balancing the weight of the blade sections 128 and 130, including the several levers 134, the links 146, and the armatures 144 of the solenoids 140 and 142 to insure the proper operation of the folding blade sections and to allow a solenoid of minimum size to be used to actuate the folding means. This means comprises a counter-weight 148 for each blade section, each counter-weight being carried by an arm or lever 150 secured to each sleeve 136. It should be noted that in the case of the folding means 8 each folding blade section 64 and 66 is counter-balanced by the weight of its crank 86, its link 84, and the weight of the operating armature 82.

The tape guiding and supporting bar 102 is provided with a plurality of bevelled article-guiding blocks 152 similar to the blocks 90 and similarly extending between the tapes 92, these bevelled blocks forming a hump in each article above the folding blade 132 to facilitate the formation of the second fold of the article.

The conveying means 14 comprises a plurality of laterally-spaced feed tapes 154, passing about rollers 156 and 158 carried by shafts 160 and 162 extending between and journaled in the side frame members 36. The forward roller 156 of the conveying means 14 is positioned in close juxtaposition to the intermediate roller 114 of the conveying means 12 and lies in a common horizontal plane with the roller 114 so as to co-operate with the folding blade sections 128 and 130 in effecting a second fold of each article. The folding fingers of each folding blade section 128 and 130 are bevelled at their upper ends so as to pass between the rollers 114 and 156 in the spaces between the tapes 110 and 154.

40   *The measuring and timing means for small articles*

The photoelectric measuring means 16 for small articles placed on the left hand side of the machine, as seen in Figure 2, comprises, as best seen in Figures 1, 2, 5, 6, 10, 29, 30, and 31, an elongated lamp 164 (Fig. 6), such as a "Lumiline" tube, positioned above and extending parallel to the line of the feed tapes 44. The lamp is mounted on and enclosed within an elongated downwardly facing trough-shaped reflector or hood 166 (Figs. 2 and 6). The hood is carried by brackets 168 fastened to transversely extending rods 170 and 172 spaced longitudinally of the machine and carried by end brackets 174 fastened to and projecting upwardly from the side members 36. Beneath the upper flight of the tapes 44 and in vertical alignment with the lamp or luminous source 164 is a travelling mirror, reflecting prism, or equivalent light-directing means 176 (Figs. 3, 5, 6, 7, 8, 10, and 29) for directing rays of light from the source 164 into a photoelectric cell 178 (Figs. 5, 10, and 11). The mirror 176 is mounted in a frame 180 in such manner as to be inclined at an angle of approximately 45 degrees so that the vertical rays of light from the source 164 will be directed horizontally into the photoelectric cell 178, which is positioned and enclosed to receive horizontally-directed rays of light. The mirror-carrying frame 180 is secured at its opposite sides by pins or bolts 182 (Fig. 7) to sprocket chains 184 passing about drive sprockets 186 (Figs. 5, 6, and 10) secured to a transverse shaft 188 and idler sprockets 190 journaled on a transverse shaft 192. The shaft 188

is journalled in the left hand side frame member 36 (Fig. 6) and in a bearing block 194 carried by a pedestal 196 supported on a transverse reinforcing frame member 198. The shaft 192 is also journalled in the left hand side frame member 36 (Fig. 5) and in a bearing block 200 supported by a similar transverse reinforcing bar not shown. The mirror 176 is guided in its forward movement by a track or rail 202 (Figs. 7 and 8) extending between the sprockets 186 and 190 and about peripheral portions of the inwardly-facing hubs of each pair of these sprockets. A second similar measuring mirror 204, similarly mounted, is also secured between the sprocket chains 184 at a distance from the measuring mirror 176 equal to one-half the overall length of a sprocket chain. Means are provided, as will be more particularly described in connection with the photoelectric measuring means 20 and 26, for maintaining the intensity of the light directed into the photoelectric cell 178 substantially constant, irrespective of the position which the measuring mirrors 176 and 204 may occupy. Means are also provided, as will subsequently be described in connection with said photoelectric measuring means 20 and 26, for preventing light from falling upon the measuring mirror 176 or the measuring mirror 204 when the mirror is in its position of rest adjacent the sprockets 190.

The photoelectric cell 178 is mounted in an enclosing housing 206 having its forward wall formed with an annular flange 208 defining an opening through which light may be directed into the housing and upon the photo-active electrode of the photoelectric cell. The flange 208 provides mounting means for an elongated funnel-shaped member 210 which prevents stray illumination of the photoelectric cell and this member 210 is provided at its outer end with a lens 212 for focusing the horizontal beam of light from the measuring mirror upon the photo-active electrode of the cell. The housing 206 may be mounted by any desired conventional bracket or clamp 214, secured to any fixed support, as, for example, to a transversely extending frame member not shown. The photoelectric cell 178, by means of the usual amplifier and relay, controls certain circuits hereinafter to be described for operating the folding blade solenoid 18 to effect the first fold of a small sheet or article placed on the left hand side of the machine and also to initiate operation of the timing means forming a part of the measuring and timing means 22.

The photoelectric measuring means 18 for small articles or sheets placed on the right hand side of the machine, as seen in Figures 2 and 5, is substantially identical in construction to the photoelectric measuring means 16 and it suffices, therefore, to note briefly that it comprises a pair of measuring mirrors 216 and 218 similar to the measuring mirrors 176 and 204 and similarly mounted between the parallel sprocket chains 220 passing about drive sprockets 222 secured to shaft 224 and about idler sprockets 226 journalled on a shaft 228. The shaft 224 is journalled in the right hand frame member 36 and in a bearing block 230 (Fig. 6) carried by a pedestal 232 in turn mounted upon the transverse frame member 198. The shaft 228 is aligned with the shaft 192 (Fig. 5) and is journalled in the right hand side frame member 36 and the bearing block 200. The measuring mirrors 216 and 218 control the reflection of light from the lamp or luminous source 234 to photoelectric cell 236. The luminous source 234 is similar to the luminous source

164 and similarly mounted in and partially enclosed by a reflector or hood 238 also secured to the transverse supporting rods 170 and 172 (see Fig. 2), the luminous source 234 being aligned vertically with the mirrors 216 and 218 and extending parallel to the path of movement of these mirrors.

A guide plate not shown but similar to the guide plate 202 for the measuring unit 16 extends between the sprocket chains 220 and partially about the peripheral portions of the inwardly-facing hubs of the sprockets 222 and 226. The photoelectric cell 236 is mounted in a housing similar to the housing 206 and is provided with a similar light-excluding and light-focusing means. The photoelectric cell 236, through a suitable amplifier and relay and by means of circuits hereinafter to be described, controls the operation of the folding blade actuating solenoid 80 to effect the first fold of small articles placed on the right hand side of the machine and this photoelectric cell also initiates the operation of the timing means forming a part of the measuring and timing means 24 located on the right hand side of the machine.

The measuring and timing means 22, as best shown in Figures 5, 6, 10, 15, 16, and 18, comprises a sprocket chain 242 passing about a drive sprocket 244, secured to the outwardly-extending end of the drive shaft 188 for the sprocket chains 184 and about an idler sprocket 246 journalled on the outwardly-extending end of the shaft 192 and held against axial movement thereon as by a collar 248 (Fig. 18). The sprocket chain 242 contains the same number of links as each of the sprocket chains 184 and is driven in synchronism therewith, being driven by the same shaft. This sprocket chain 242 is provided on its inner edge with a pair of outwardly projecting lugs 250, positioned so as to lie at all times in the same transverse plane with the mirrors 176 and 204, the lugs therefore being spaced apart on the sprocket chain 242 a distance equal to one-half of the overall length of this sprocket chain. The lugs 250 of the sprocket chain 242 are each adapted to engage the side of an outwardly-projecting arm 252 of a slide member 254 which comprises, in addition to the arm 252, a reciprocable member 256 slidably mounted on vertically spaced guide rods or bars 258 and 260. The guide rod 258 is fixedly mounted in longitudinally spaced brackets 262 and 264 bolted or otherwise secured to the left hand side frame member 36.

The bar 260 is oscillatably mounted in the brackets 262 and 264. The arm 252 is mounted for upward oscillation with the bar 260 and for this purpose it is secured to a sleeve 266 passing through the lower web of the slide 256 and mounted on the bar 260 for rotation therewith. Downward movement of the arm or lever 252 is limited by the arm 268 of the stop member 270, secured to the opposite end of the lower web of the slide 256 and interlocked with the sleeve 266 in any convenient manner as, for example, by means of a pin received in a circumferential groove in the sleeve to prevent axial movement of the sleeve relative to the slide. The bar 260 is oscillated in a counter-clockwise direction, as seen in Figures 15 and 18, to raise the arm or lever 252 by means of a solenoid 272 (Fig. 15). This solenoid, as subsequently to be described, also controls a clutch mechanism 274 for connecting the driving mechanism to the timing means or double chain 276 which co-

operates with the slide member 254 of its associated measuring means to effect the second fold of small articles placed on the left hand side of the machine. The bar 260 is provided with an operating crank 278 pivotally connected at its outer end to a rod or pitman 280, the rod 280 being enlarged at its lower end to provide a web portion 282 (Figs. 15 and 16) having a slot 284 extending therethrough. The slot 284 is shaped in the form of an inverted L and receives a pin or rod 286 of a clutch control yoke or frame 288, the rod 286 being connected to the armature 290 of the solenoid 272 by a link 292. The rod 280 is moved in an upward direction to oscillate the bar 260 in a clockwise direction to return the arm 252 to its generally horizontal position in the path of the lugs 250 of the chain 242 by a spring or the like 294 secured at one end to the frame of the machine and at its other end to the web portion 282 of the rod 280. A cam bar or strap 296 is mounted on the supporting frame for the solenoid 272 and extends upwardly therefrom at an appropriate angle to engage the web portion 282 of the rod 280 as it is moved downwardly by the solenoid-operated rod 286 and moves this rod 280 rearwardly relative to the rod 286 so that the vertical portion of the slot 284 will be aligned with rod 286, thereby permitting the rod 280 to move upwardly under the action of the spring 294, even though the rod 286 is held in its lowered position. This connection between the rod 280 and the clutch-controlling yoke or frame 288 permits the rod 280 to be operated downwardly simultaneous with the operation of the clutch-controlling yoke or frame but allows the rod 280 to be moved upwardly to return the arm 252 to its normal horizontal position as soon as the driving lug has passed beyond this arm, while at the same time allowing the frame or yoke to remain in its lower position for a definite period of time.

The slide member 254 carries a frame or housing for a second fold control switch 298 which is provided with an operating lever 300 that is operated by the timing means or chain 276, as hereinafter described.

The slide member 254 and the measuring mirrors 176 and 204 of the photoelectric measuring means 16 are operated in synchronism at all times in a direction opposite to the direction of movement of the article or sheet to be folded and at a speed equal to the speed of movement of this article or sheet. When the measuring mirror 176 or 204, as the case may be, passes out from under the rear edge of the sheet, it causes operation of the photoelectric cell 178 which, by means of a suitable circuit hereinafter to be described, actuates the folding blade solenoid 18 and simultaneously actuates the solenoid 272 which instantaneously operates the arm 252 of the slide member 254 to release this slide member from the chain 242. Therefore, this slide member 254 moves to the right a distance substantially equal to one-half the length of the sheet, as will subsequently be made more apparent. The slide member 254 is thereupon moved rearwardly or toward its original position of rest. This movement of the slide member is accomplished by means of a chain, cable or the like 302 secured at one end to the frame 298 and passing rearwardly therefrom about a pulley 304, freely journalled on the shaft 192, and forwardly to a drum 306 about which the other end of the chain is wrapped. The drum 306 constitutes a part of a friction clutch 308 shown in detail in

Figure 20. The drum 306 is journalled on a sleeve 310, in turn journalled on a fixed stud 312 carried by and projecting outwardly from the frame member 36. The drum 306 is provided with a plurality of angularly spaced axially extending openings 314 for receiving coil springs 316. The springs 316 at their outer ends act against a disk 318 provided with pins 320 received within the springs 316. The drum 306 and the disk 318 are interposed between friction disks 321 and 322 and the whole clamped on the sleeve 310 by a collar 324 and the hub of a sprocket 326, the collar 324 and the sprocket 326 being secured to the sleeve as by a plurality of angularly spaced screws 328 and 330 received in threaded openings in the sleeve, the collar and the sprocket. The sprocket 326 is driven by the timing means or chain 276 and is clamped with the clutch 308 and the collar 324 against axial movement on stud 312 by means of collars 332. The springs 316 are so proportioned in size that the clutch 308, when driven by the sprocket 326 through the friction disks 320 and 322, exerts only enough force on the chain 302 to move the slide member 254 along the guide bars 258 and 260 but will allow the clutch to yield or slip readily when the slide member is moved by the chain 242 or is stopped by engagement with the bracket 262.

The timing means 276 comprises a double sprocket chain consisting of chains 334 and 336, secured together as by means of common transverse pins extending through the links of both chains, the chain 334 being a driving chain and the chain 336 being a control chain for controlling the operation of the clutch mechanism 274. The chain 334 is continuous and is composed of the same number of links as the chain 242 and as the chains 184 of the photoelectric measuring means 16. The chain 336 is discontinuous. More specifically, a certain number of links of this chain 336 are removed at two points so that the chain may perform its clutch-controlling function. The chain 336 also carries a pair of lugs 338 and 340 which are spaced apart a distance equal to one-half the length of the chain 334 and operate the switch-operating lever 300 to close the switch contacts controlled thereby. The switch-operating lever 300 may be provided, if desired, with adjustable means for precisely predetermining the instant of operation of the lever by the lugs 338 and 340. As shown in Figure 19, this means may comprise a block 342, adjustably mounted on the lever 300 as by screws 344 received in an elongated slot or slots 346 at the forward end of the lever 300.

The clutch mechanism 274 which drives the timing means or chain 276 must be capable of instantaneous operation to initiate movement of the chain; it must be capable of moving the chain a predetermined distance each time that it is operated, and it must be capable of permitting slippage between its driving and driven parts without generation of any substantial amount of heat.

To this end applicant has provided the clutch shown in Figs. 21 to 25 inclusive. The driving clutch member comprises a disk 348 having its hub portion 350 splined to the driving shaft 352. The driven clutch member comprises a disk 354 having an annular flange 356 overlying the disk 348 to which annular flange is bolted the face plate or clutch disk 358 extending over the outer face of the disk 348. A friction disk or ring 360 is interposed between the outer face of the disk

348 and the inner face of the plate or disk 358. An auxiliary disk and clutch control member 362 is journaled on the shaft 352 and is free for limited axial movement on the shaft. A second friction disk or ring 364 is interposed between the inner face of the disk 348 and the outer face of the disk 362. The driven clutch member 354 is journaled on the shaft 352 by the bushing or sleeve 366 and is secured to the drive sprocket 367 for the chain 334 of the double timing chain 276 as by the screws 368 which also fasten a collar 370, journaled on the shaft 352, to the clutch member 354.

The disk 362 is carried by a pair of diametrically spaced pins 372 slidably mounted in the disk 354 and in a hardened steel collar 374 secured to the hub of this disk. Coil springs 376 received in pockets 378 in the disk 354, embrace the pins 372 and bear against the disk 362 to urge this disk axially to the left as seen in Figs. 21 to 23 to compress the friction rings 360 and 364 thereby to frictionally connect the driving clutch member 350 to the clutch disks 358 and 362 and through these clutch disks and the pins 372 to the driven clutch member or disk 354. Axial movement of the clutch disk 362 to the right to release the driving connection between the driving and driven clutch members is effected by means of the clutch control yoke 288 which for this purpose is provided on its forward arm 380 with an upwardly projecting cam 382 having on its forward edge the beveled cam face 384 controlling the movements of a generally U-shaped hardened steel wobble plate 386 secured to the pins 372 at their outer ends as by the transverse pivot pins 388, the pins 372 being received within enlarged openings 390 in the arms of the wobble plate. The wobble plate 386 is fulcrumed on the hardened steel collar 374 by the engagement of its free edges 392 with the face of this collar 374. The wobble plate carries a pin 394 provided with a rounded head to engage the cam 382. It will be evident that as the yoke 288 is moved upwardly, the cam 382 is projected between the outer face of the disk 354 and the wobble plate 386 and the beveled edge 384 of this cam engaging the pin 394 forces this wobble plate in a counter-clockwise direction as seen in Fig. 21, thereby to move the pins 372 and the clutch disk 362 axially to the right to release the clutch rings 360 and 364, it being noted that the driving clutch disk 348 is mounted in a manner to permit a limited axial movement so that upon release of the clutch disk 364, the clutch disk 360 will also be released. An adjustable pin 396, carried by the disk 358 and the disk 354, in passing through the annular flange 356 of this last disk projects beyond the outer face of the disk 354 to engage a face of the cam 382 opposite the pin 394 to prevent warping of this cam by its repeated operation. The yoke member 288 is normally retained in its upper position by means of a coil spring 398 connected between the rear arm 400 of the yoke and a fixed abutment or pin 402 (Fig. 15) on the frame of the machine, in which position the cam 382 projects between the disk 354 and the wobble plate 386 to hold the wobble plate in clutch releasing position, thus rendering the clutch normally ineffective to drive the sprocket 367.

The number of revolutions of the sprocket 367 for each operation of the clutch is determined by the discontinuous chain 336 of the double-timing chain 276 by means of a cam or stop

404 mounted on the rear arm 400 of the yoke member 288 (Fig. 24). This cam or stop 404 is normally in engagement with the periphery of the collar 370 as shown in solid lines in Fig. 24, and projects into the longitudinal plane of the chain 336 in the space between portions of this chain. Upon energization of the solenoid 272, the yoke member 288 is moved downwardly, thereby removing the cam or stop 404 from the path of the chain 336 and the cam 382 being simultaneously moved downwardly, the clutch 274 is rendered operative to drive the sprocket 367 and the chains 334 and 336. The solenoid 272 is only instantaneously operative, but the clutch 274 operates through a predetermined number of revolutions, and the cam 404 retains the yoke member 288 in its lower position after the solenoid has become deenergized, because after operation of the chain 336 has been initiated, the links thereof overlie the cam 404, as shown in dotted lines in Fig. 24, and prevent its upward movement. In order to permit free movement of the links of this chain 336 across the cam 404, the upper edge thereof is curved inwardly as at 406. When the clutch 274 and the sprocket 367 have rotated through a predetermined number of revolutions, a second portion of the chain 336, from which the links have been removed, reaches the cam 404 and this cam therefore moves upwardly under the force of the spring 398, thereby allowing the cam bar 382 to operate the wobble plate 386 to render the clutch ineffective and engaging the forward link of the next portion of the chain 336, thereby acting as a positive brake on the timing chain 276.

The yoke 288 is pivoted on the left hand side frame member 36 for this upward and downward movement by a pin or stud shaft 408 carried by the frame member and the sleeve 410 extending between the arms 380 and 400 of the yoke.

The lugs 338 and 340 carried by the chain 336 of the double-timing chain 276 control the operation of the traveling second fold control switch 298. As this traveling switch 298 moves rearwardly following its release from the chain 242, the timing chain 276 is driven in an opposite direction by the clutch 274 for the operation of this clutch is initiated at the same instant that the switch-carrying carriage or slide member 254 is released from the chain 242. The timing chain 276 is always driven in a clockwise direction as seen in Figs. 15 and 18 and therefore after the lapse of a predetermined time, which time is determined by the position of the switch-carrying carriage at the instant of its release from the chain 242, one of the lugs 338 and 340 engages the switch arm 300 (Fig. 15) or the adjustable lug 342 carried by this arm as in Fig. 19, and moves this switch arm upwardly, thereby operating the second fold control switch 298. This control switch, through circuits subsequently described, controls the energization of the solenoid 140 to effect the second fold of small articles or sheets on the left hand side of the machine. Electrical connection to the traveling switch 298 is effected through a cable 412 (Fig. 18) wound at its forward end about a spring-operated drum (not shown), enclosed within a housing 414 carried at the upper edge of the left hand side frame member 36.

It will be evident that since the forward movement of the traveling switch carriage is controlled by the photoelectric cell 178 of the meas-

uring means 16, it will move forward a distance equal to substantially one-half the length of the article in the machine, and will be released for rearward movement at the same time that the first fold is formed in the article. It moves rearwardly at a speed which is definitely proportioned to the speed of movement of the sheet for in this rearward movement it is operated by the double-timing chain 276 through the clutch 308. The switch-operating lug moves in the opposite direction to the traveling switch carriage 254 from a fixed point of rest and its speed of movement is also definitely proportioned to the movement of the article, since it is carried by the double-timing chain 276. The switch-operating lugs are so positioned on the timing chain that at the instant one of the lugs operates the control switch 298, the center of the once-folded article is substantially positioned above the folding blade section 128 to effect the second fold of the article.

The measuring and timing means 24 for effecting the second fold of small articles or sheets placed on the right hand side of the machine as seen in Figs. 2 and 5, is substantially identical in construction to the measuring and timing means 22 and it suffices therefore to note briefly that it comprises a sprocket chain 416 (Fig. 10) corresponding to the sprocket chain 242 and passing about an idler sprocket 418 on the shaft 228 and to drive sprocket 420 on the extending end of the shaft 224. The chain 416 controls the forward movement of a traveling switch carriage not shown but identical to the traveling switch carriage 254 and the release of this carriage from the chain 416 for rearward movement is controlled by the photoelectric cell 236 of the measuring means 18 at the same instant that the photoelectric cell through suitable circuits hereinafter described operates the folding blade section 66 to effect the first fold of small articles or sheets on the right hand side of the machine. A timing means or double-timing chain 422 similar to the double-timing chain 276 is driven by a clutch 424, corresponding to the clutch 274, and controls the rearward movement of this traveling switch carriage through a clutch 426 (Fig. 10) corresponding to the friction clutch 308, and lugs corresponding to the lugs 338 and 340 are provided on the double-timing chain 422 to operate the traveling second fold control switch 428 shown schematically in Figs. 32 and 33, but similar to the second fold control switch 298, for controlling the energization of the solenoid 142 to effect the second fold of small articles or sheets on the right hand side of the machine. The clutch 424 and the timing means or double-timing chain 422 are controlled by cams 430 and 432 (Fig. 6), corresponding to the cams 382 and 404, which are carried by a yoke or frame 434 similar to the yoke 288. The yoke 434 is operated by solenoid 436 similar to the solenoid 272 and similarly connected to this yoke 434. The traveling switch carriage on this right hand side of the machine is released from the chain 416 by the operation of the yoke 434 through a structure corresponding to that shown in Figs. 15 and 18.

The measuring means or mechanisms for large articles

The photoelectric measuring means 20 for large articles comprises as best shown in Figs. 2, 5, 6, 10 and 14, an elongated luminous source 438 (Fig. 6) similar to the source 164 and simi-

larly mounted in a reflector hood 440 (Fig. 2) which in turn is mounted on the transverse bar 170 and a corresponding bar 442 spaced forwardly of the bar 170 and mounted between the side frame members 36 by means of the brackets 444. Beneath the upper flight of tapes 44 and in vertical alignment with the luminous source 438 is a traveling mirror, reflective prism, or equivalent light directing means 446 (Fig. 10), similar to the light directing means 176 of the measuring means 16, but facing in the direction of movement of the large articles to direct the luminous rays from the source 438 horizontally upon a photoelectric cell 448 (Fig. 5) positioned in the plane of movement of the mirror 446, but to the rear of the chains 450 which carry this mirror 446. The sprocket chains 450 pass about idler sprockets 452 carried by a transverse stud shaft 454 journaled in suitable fixed brackets 456 and about drive sprockets 458 secured to a shaft 460 aligned with the shafts 188 and 224 journaled in the same bearings 194 and 230. It should be noted that the chain 450 carries only one measuring mirror 446 and this mirror is positioned when at rest to extend downwardly from the lower flights of the chains as shown in Figs. 10 and 26. The photoelectric cell 448 is mounted in a housing similar in all respects to the housing 206 as shown in Fig. 11, and controls through the circuits hereinafter described, the solenoids 78 and 80, to energize these solenoids when the mirror 446 passes out from under the rear edge of a large article or sheet.

The photoelectric measuring means 26 comprises an elongated luminous source or lamp 462 (Fig. 6) in an elongated reflector hood 464 secured by suitable brackets to the transverse bars 170 and 172 (Fig. 2). A pair of sprocket chains 466 positioned between the upper and lower flights of the tapes 44 and extending longitudinally of the tapes passes about idler sprockets 468 (Figs. 5 and 10) on the shaft 460 and drive sprockets 470 secured to the shaft 192. The chains 466 support a pair of mirrors, reflecting prisms or equivalent light directing means 472 and 474 similar to the mirror or light directing means 176 and similarly secured to the chains 466, the mirrors 472 and 474 being spaced a distance equal to one-half the length of the sprocket chain and facing forwardly of the machine as they move with the upper flight of the chain. A photoelectric cell 476 is mounted in a housing similar to the housing 206 of Fig. 11 and which housing is, similarly to the housings for the other photoelectric cells, provided with the lens 212 and the funnel-shaped tube or hood 210 for preventing stray illumination of the photoelectric cell. The photoelectric cell 476 is positioned forwardly of the machine in advance of the chains 466, but positioned in the same horizontal plane as the plane of movement of the mirrors 472 or 474 along the upper flights of the chains. The photoelectric cell 476 controls the solenoids 140 and 142 for energizing the solenoids simultaneously when the mirror 472 or the mirror 474 passes from under the rear edge of a once-folded large article or sheet, thereby to effect the second fold of this large article or sheet.

Means are provided for maintaining the quantity of the light directed into each of the photoelectric cells 178, 236, 448 and 476 substantially constant irrespective of the position which its associated measuring mirror may occupy, and means are also provided for preventing light from falling upon each of these photoelectric cells when

their associated mirrors are at rest. These means are substantially identical for each of the photoelectric measuring means and therefore such means are illustrated in detail only in connection with the central photoelectric measuring units 20 and 26. As shown in Fig. 14, a plate 478, secured to the transverse channel bar or shelf 488 and extending beneath the tapes 44 over the mirror 472 (or the mirror 474) when the mirror is in its normal position of rest relatively adjacent the forward end of the mirror guide track or plate 480. It will be evident that the plate 478 prevents the rays from the luminous source 462 from falling upon the mirror 472 (or the mirror 474) when the mirror is in this rest position. Therefore in the normal inactive position of the measuring unit, the light from the source 462 will not be directed into the photoelectric cell 476. In order to maintain the quantity of the light at the photoelectric cell substantially constant irrespective of the position which the mirror occupies at the instant that it passes from under the rear edge of an article, a pair of plates or bars 482 and 484 are provided underlying the tapes 44 and secured at their forward ends to a plate or shield 486 which is secured to a transversely extending bar 488 forming a transverse guide for the feed tapes 44 (Fig. 6) and mounted at its opposite ends on the transverse reenforcing frame member 198. The shield 486 extends over the housing for the photoelectric cell 476 and provides additional means for preventing stray illumination of the photoelectric cell. The bars 482 and 484 are angularly disposed relative to each other, or have their adjacent edges disposed angularly so as to provide between these bars a space of constantly decreasing width so proportioned that as the quantity of light for a given area at the plane of the photoelectric cell increases at the approach of the mirror 472, the area of the beam will decrease, thereby tending to retain the quantity of the light reflected onto the mirror substantially constant. A similar pair of light-controlling plates 490 and 492 are provided in connection with photoelectric measuring unit 20 and these bars are secured at their rear edges to the shield 486 and at the forward edges to any suitable support not shown, but which may comprise a bracket mounted on a transverse auxiliary frame member. In the case of the bars 490 and 492, or their equivalent slotted plate, the mirror 446 moves forwardly of the machine while facing rearwardly thereof and therefore these bars or plate are so arranged as to allow a constantly increasing quantity of light to be reflected by the mirror as the mirror in moving forwardly causes the quantity of the light at the plane of the photoelectric cell to be decreased, thereby maintaining the quantity of light in this plane substantially constant. Since the shield 486 extends over a portion of the chains 450 for the unit 20, it is broken away in the plane of the bars 490 and 492 to permit the light from the source 438 to pass between these bars the full length of the chains. A shield or plate 494 is secured to the bar 488 and extends over the housing of the photoelectric cell 448 to provide an additional means for excluding light, other than that from the mirror 446, from the photoelectric cell. A guide track or rail 496 shown fragmentarily in Fig. 14, but similar to the guide 480 and the guide 202, supports the mirror 446 in its movement with the upper flights of the chains 450. The photoelectric measuring units 16 and 18 are provided with light-directing and controlling

shields similar to the light-directing and controlling shields 478, 482, 484 and 486 for the measuring unit 26, it being noted however that for these units 16 and 18 the shields corresponding to the shield 478 are mounted on the transverse bar 88 above the forward ends of the chains 184 and 220.

The driving mechanism

10 As best shown in Figs. 3, 5, 6, 7, and 10, the driving mechanism comprises the electric motor 500 mounted between the side frame members 36 upon any suitable platform or frame, the shaft of the motor being coupled with the shaft 352 by a belt or chain 502 and a pulley or sprocket 504 secured to the shaft 352. The shaft 352 carries a plurality of clutches 506, 508 and 510 which are identical in construction to the clutch 274, which latter clutch as well as the clutch 424, is mounted on the shaft 352 as previously described, the shaft 352 being journaled in the side frame members 36 and also in any number of suitable and desired bearings (not shown) carried by a suitable cross-member or up-right between the side frame members. A clutch 506 drives the shaft 188 a predetermined number of revolutions by means of a double chain 512 and 514 similar to the double chain 276, the drive chain 512 passing about a drive sprocket 516 secured to the driven element of this clutch, a driven sprocket 518 secured to the shaft 188, and an idler sprocket 520 mounted on a stud shaft carried by the left hand side frame member 36. The chain 514 is discontinuous similar to the chain 336 of the double chain 276 and similarly controls the number of revolutions of the driven clutch member for each operation of the clutch 506. The clutch 508 drives the shaft 460 through a predetermined number of revolutions for each operation of the clutch by means of a double sprocket chain 522 and 523, the drive chain 522 of which passes about a drive sprocket 524 secured to the driven member of this clutch, a driven sprocket 526 secured to the shaft 460 and an idler sprocket 528 mounted on a stud shaft carried in a suitable bracket not shown, which may be secured to one of the transverse auxiliary frame members. It may be noted at this point that the double sprocket chains 522 and 523 of the unit 20 are twice as long as the sprocket chains 512 and 514 of the unit 16. Because the chains 450 of the measuring unit 20 are provided with only a single mirror 446, the chains 450 must be moved their complete length to bring the mirror back to its normal rest position, but in the case of the unit 16, the chains 184 need be driven only a distance equal to one-half their length to position their mirrors in the normal rest or starting position. The chain 523 controls the clutch 508 to render it ineffective after a predetermined number of revolutions in the same manner as the chain 336 renders the clutch 274 ineffective after a given number of revolutions. The clutch control chains 514 and 523, however, differ from the clutch control chain 336 in that the links are removed only from one section, whereas in the case of the chain 336, the links are removed from two portions spaced apart one-half the length of the chain. The clutch 510 drives the shaft 224 through a double sprocket chain 530 and 532 similar to the chains 334 and 336 of the double chain 276. The driving chain 530 of this pair of chains passes about a drive sprocket secured to the driven member of the clutch 510, a driven sprocket 536

secured to the shaft 224, and an idler sprocket 538 mounted on a stud shaft carried by the right hand frame member 36. The chain 532 controls the clutch 510 in the same manner that the chain 334 controls the clutch 274, but the chain 532 is only half as long as the chain 334 and has a set of links removed only from one portion thereof instead of from two as in the case of the chain 334. Operation of the clutches 506, 508 and 510 is initiated by solenoids 540, 542 and 544 respectively, (Fig. 6) by means of yokes or frames 546, 548 and 550 respectively. The yokes 546, 548 and 550 are similar in all respects to the yoke 288 (Fig. 15) and each carries on its spaced arms, cams similar to the cams 382 and 404 for controlling the wobble plate of the clutch and for engaging the discontinuous chain to maintain the other cam out of engagement with the wobble plate during movement of the driven member of the clutch through a predetermined number of revolutions. In the case of the clutches 506, 508 and 510, means must be provided to prevent overrunning of the clutches as their control solenoids remain energized during the entire operation of their associated measuring units and therefore in the case of these clutches the solenoids are connected to the clutch control yokes in a manner different from the connection between the solenoid 272 and the yoke 288. In Fig. 17 is shown the connection between the solenoid 542 and the yoke 548. It will be understood that this is illustrative of the connection between the solenoid 540 and the yoke 546 and the connection between the solenoid 544 and the yoke 550. The transverse pin 552 of the yoke 548 is normally received within a notch 554 of a bar 556 pivoted at its lower end to the armature 558 of the solenoid 542. The bar 556 is provided with a laterally and downwardly extending arm 560 which, as the bar 556 moves downwardly upon energization of the solenoid, engages a lug 562 carried by the solenoid frame or the support bracket for the solenoid. The lug 562 upon engaging the arm 560 pivots the bar 556 in a counter-clockwise direction as seen in Fig. 17 and releases the cross-pin 552 of the yoke 548 from this bar and allows the yoke to move upwardly under the force of a spring 564 secured to one arm of the yoke and to a fixed lug carried by any suitable fixed frame member or bracket. The cams carried by the yoke 548 are therefore positioned to exert their controlling action on the clutch as determined solely by the discontinuous clutch control chain 523. Upon deenergization of the solenoid, a spring 566 secured at one end to the bar 556 and suitably fixed at the other end moves the bar upwardly to reposition the cross-pin 552 of the yoke in the notch 554 so that the solenoid 552, if instantaneously reenergized, may again operate the clutch 508.

The feed tapes 44 of the conveyor 4 are driven by the drum 46 (Fig. 2) and this drum is driven by means of a sprocket chain 568 (Fig. 3) which passes about a drive sprocket 570 secured to a stud shaft 572 journaled in the left hand side frame member 36, an idler sprocket 574 journaled or mounted on stud shaft 576 also journaled in the left hand frame member 36 and about the driven sprocket 578 secured to the shaft 50 to which the drum 46 is also secured. If desired, the shaft 50 may be used as a bearing and the sprocket 578 secured directly to the left end of the drum 46 as seen in Fig. 2. The sprocket chain 568 also drives the feed tapes 92, 110 and 114 of the conveyors 10, 12 and 14, and

for this purpose the sprocket chain 568 passes from the sprocket 578 rearwardly of the machine to sprockets 580, 582, 584 and 586 and returns to the drive sprocket 570 over the idler sprockets 588 and 590. The sprockets 580, 582, 584 and 586 are mounted on the shafts 120, 98, 122 and 160 respectively and drive the drums or rollers 112, 94, 114 and 116 respectively (Fig. 8). The idler sprocket 588 is freely journaled on the shaft 192, and the idler sprocket 590 is mounted on a shaft 592 carried by the left side frame member 36. The shaft 592 may extend through this frame member 36 to constitute a support for the idler sprocket 594 (Fig. 10) about which the double timing chain 276 passes.

The shaft 572 is driven by the main drive shaft 352 by means of a gear 596 secured to the shaft 352 and intermeshing with a gear 598 secured to the shaft 572, these gears being preferably housed within the inner and outer walls of the left frame member 36.

The feed tapes for each of the conveyors 4, 10, 12 and 14 are driven at the same speed as each of the chains 184, 220, 450 and 566 of the photoelectric measuring units 16, 18, 20 and 26 and at the same speed as the chains 242 and 416 of the measuring and timing means 22 and 24. The timing chains 276 and 422 and the clutch-controlling sets of double chains 512—514, 522—523 and 530—532 are also driven at the same speed as the feed tapes.

The operating solenoids 540, 542 and 544 for the clutches 506, 508 and 510 are controlled by photoelectric cells 600, 602 and 604 respectively (Fig. 10) which are mounted on a bar 606 (Fig. 8) extending between the side frame members 36 and secured thereto. The photoelectric cell 602 is mounted in the housing 608 (Fig. 12), adjustably clamped to the bar 606 in the manner indicated in Fig. 8 with reference to photoelectric cell 600. The housing 608 is provided in its upper wall with an annular flange 610 defining an opening through which light may pass to the photoelectric cell 602 and on this annular flange 610 is mounted a tube 612 carrying at its upper end a lens 614. The housing 608 and the tube 612 exclude rays of light other than those directed in a generally vertical direction upon the photoelectric cell 602. The photoelectric cells 600 and 604 are mounted in housings similar to the housing 608 and provided with similar stray light-excluding tubes and light-focusing lenses. These photoelectric cells 600, 602 and 604 are each positioned between an adjacent pair of feed tapes 44, the photoelectric cell 602 being positioned substantially in the central longitudinal plane of the machine and the photoelectric cells 600 and 604 being positioned towards the left hand and the right hand sides of the machine respectively, so that large articles or sheets will pass over the photoelectric cells 602 and 600 and small articles or sheets will pass over either the photoelectric cell 600 or the photoelectric cell 604. These photoelectric cells normally receive beams of light from lamps 616, of which one only is shown in Fig. 8 inclosed in suitable reflectors 618 (Figs. 2 and 8) and mounted with the reflectors on sockets 620 carried by brackets 622 secured to the transverse bar 172. The lamps 616 are so positioned as to direct beams of light in a generally vertical direction as seen in Fig. 8 between pairs of the tapes 110 and pairs of the tapes 44 in planes passing between the rollers or drums 94 and 112, and upon the photoelectric cells 600, 602 and 604 positioned in these same generally vertical

planes, so that the beams of light from the lamps 616 will be interrupted by the forward edge of articles or sheets when they reach the first folding blade sections 64 and 66. Upon interruption of their light beams, these photoelectric cells through suitable circuits hereinafter described, operate the clutch solenoids 540, 542 and 544 to initiate operation of the photoelectric measuring units 16, 18 and 20 respectively, and also to exert other controlling functions as will hereinafter be made apparent.

Operation of the machine to fold small articles

A small sheet fed to the left hand side of the machine by the conveying mechanism of the ironer 58 or otherwise is carried by the feed tapes 44 to a position at which, as shown in Fig. 29, it interrupts at its forward edge the beam of light normally projected upon the photoelectric cell 600. The photoelectric cell 600 is connected by a cable 623 to the amplifier of an amplifier controlled relay 624 (Fig. 32) of any suitable conventional structure such that its controlled switch 626 is closed upon interruption of the beam of light upon the controlling photoelectric cell. The amplifier-relay 624 and each of the relays hereinafter described are mounted in housings, such as 40, formed in the side frame members 36 and enclosed by the cover plates such as shown at 42 in Fig. 1. Closure of the switch 626 connects a relay 628 to the power lines L-1 and L-2 by means of wires 630, 632, 634 and 636 to the line L-1 and from the line L-2 by the wires 638, 640 and 642 back to the switch 626. The wires 634 and 640 also constitute the power leads for the amplifier-relay 624. The relay 628 upon energization completes a circuit to the clutch-operating solenoid 540, which operates the clutch 506 and connects the shaft 188 (Fig. 10) to the main drive shaft 352. This circuit is completed from the supply line L-1 through the wire 636, the wire 644, the second arm of the switch 646, counting from the top, the wire 648, the solenoid 540, the wire 650, the upper arm of the switch 646, the wire 652 and the wire 638 to the supply line L-2. This causes operation of the chains 184 of the photoelectric measuring unit 16 and moves the mirror 176 (or the mirror 204) in a direction opposite to the direction of movement of the article and at a speed equal thereto. The slide member 254 carrying the second fold control switch 298 on the left hand side of the machine moves forward with the mirror 176 and in synchronism therewith since the chain 242 is driven from the same shaft as the chains 184. As the mirror 176 (or the mirror 204) passes the rear edge of the article or sheet, it reflects light from the source 166 into the photoelectric cell 178. The photoelectric cell 178 through an amplifier-relay 654, which closes its contact 656 upon an increase in the illumination of the photoelectric cell, completes a circuit to a relay 658. This circuit is completed from the supply line L-1 through the wire 638, the wire 660, switch 656, relay coil 658, the wire 662, the wire 664, and the wire 638 to the supply line L-2. The relay 658 completes a circuit to the first folding blade solenoid 78 and a circuit to clutch control solenoid 272. The circuit to the folding blade solenoid 78 which effects a first fold of the article or sheet is completed from the supply line L-1 through the wire 636, the wire 666, the lower arm of the switch 668 controlled by the relay 658, the wire 670, the wire 672, solenoid 78, the wire 674, and the wire 638 to the supply line L-2. The 75

circuit to the solenoid 272 which effects release of the slide member 254 from the chain 242 is completed from the supply line L-1 through the wire 636, the wire 676, the solenoid 272, the wire 678, switch 680, the wire 682, the upper arm of the switch 686, the wire 684, and the wire 638 to the supply line L-2.

Operation of the solenoid 272, in addition to releasing the slide member which carries the second fold master control switch 298, also initiates operation of the clutch 274 (Fig. 15). The clutch 274 operates through a predetermined number of revolutions as previously described to drive the timing means or chain 276 through a certain distance, to wit, one-half its length. During the movement of the chain 276, slide member 254 is moved to the left in Fig. 15 under the action of the friction clutch 308 which is also driven by the chain 276. When one of the lugs 332 or 340 carried by the chain 276 engages the operating arm of the travelling switch 298, it completes the circuit to the second folding blade solenoid 140 to effect a second fold of small articles or sheets on the left hand side of the machine. The switch 298 completes the circuit from the supply line L-1 through the wire 686, the relay 688, the wire 690, the switch 298, the wire 692, the wire 694, the second, normally closed, contact of switch 696, the wire 698 and the wire 700 to the supply line L-2. The relay 688, when energized, operates its switch 702 to complete a circuit from the supply line L-1 through the wire 704, switch 702, the wire 706, the second folding blade solenoid 140, the wire 708, and the wire 638 to the supply line L-2. This effects the energization of the solenoid 140 to effect the second fold of small articles on the left hand side of the machine.

Figs. 29 to 31 illustrate graphically the sequence of mechanical operations to effect folding of the small article as previously described. Figure 29 illustrates the position which the small article, indicated by the reference numeral 710, occupies when its forward edge interrupts the beam of light passing from one of the lamps 616 to the photoelectric cell 600. At this instant, the mirrors 176 and 204 occupy the rest positions shown in this figure, the mirror 176 being positioned to effect a measuring operation when moved to the right by the chains 184. The photoelectric cell 600 at this instant energizes the clutch operating solenoid 540 illustrated graphically in Fig. 30. The solenoid 540 pulls down the bar 556 to lower the clutch yoke 546 and release the clutch 506 for operation through a predetermined number of revolutions. The clutch 506 through the double chain 512-514 operates chain 184 to move the mirror 176 to the right until it occupies the position shown in Fig. 30, in which position the mirror passes from beneath the rear edge of the sheet and the light from the luminous source 164 is directed into the photoelectric cell 178, which, as previously described, causes operation of the first folding blade solenoid 78. The travelling second fold control switch 298 moves synchronously with the mirror 176 and when the mirror reaches this position the switch reaches a corresponding position shown in dotted lines in Fig. 31. The solenoid 540 is maintained energized by the photoelectric cell 600 since the beam of light remains interrupted by the sheet 710. However, the yoke 546 has been released from the bar 556 as previously described and hence, when the clutch 506 completes its predetermined number of revolutions, this yoke is in its upper position to prevent further movement of the driven part of the clutch

and hence, after the mirror 178 has passed from beneath the sheet, it continues to move until the mirror 204 is brought to the position which the mirror 176 occupied in Fig. 29. When the photoelectric cell 178 is actuated by the mirror 176 to operate the first folding blade solenoid 78 it also causes operation of the clutch solenoid 212 as previously described. This clutch solenoid releases the travelling switch 298 from its driving chain 242 and now causes the travelling switch to move in the opposite direction until it reaches the position shown in solid lines in Fig. 31, in which position the lug 338 (or the lug 340) engages the switch arm 300 to operate this switch and complete the circuit as heretofore described to the second folding blade solenoid 140, which thus effects the second fold of the sheet 710. The travelling switch 298, however, continues its movement until it reaches its original position of rest which is against the bracket 262 in Fig. 18 and the chain 276 also continues its movement until the next of the two lugs carried by it reaches its rest position.

It should be noted that, since the mirror 176 (or the mirror 204) travels oppositely to the sheet and at the same speed, its distance of movement is substantially the distance of movement of the sheet from the position shown in Fig. 29 to the position shown in Fig. 30, which distance is, of course, equal to one-half the length of the sheet. Theoretically, this distance of movement of the mirror should be exactly equal to one-half of the length of the sheet. In actual practice, however, it is found that it requires a certain length of time following the activation of the photoelectric cell 178 to effect an engagement of the folding blade with the sheet. This operating interval or allowance is, of course, constant and independent of the length of the sheet. Therefore, in actual practice, the mirror is adjusted with respect to its operating chains in advance of its theoretical rest position so that it will pass from beneath the rear edge of the sheet sufficiently prior to the time that the center of the sheet is above the folding blade to compensate for this operating interval or allowance.

Since the second folding blade is spaced from the first folding blade a certain fixed distance, the travelling switch 298 must theoretically move to the left from its dotted line position shown in Fig. 31 a distance equal to one-fourth the length of the sheet plus the fixed distance between the first and second folding blades. In actual practice, however, compensation must be made for the operating interval required to engage the second folding blade with the sheet following the operation of this switch 298. Therefore, although the switch 298 may be said to move a distance substantially equal to one-fourth of the length of the sheet, this distance is actually somewhat less to provide this operating allowance and, accordingly, the lugs 338 and 340 are advanced on the chain 276 relative to theoretical rest positions.

The mechanical operation of the photoelectric measuring unit 18 to effect the first fold of an article on the right hand side of the machine is identical with that previously described with respect to the photoelectric measuring unit 16 and the mechanical operation of the measuring and timing means 24 to effect the second fold of articles on this side of the machine is identical to the operation of the measuring and timing means 22. However, the electrical circuit which is controlled by these units and which controls

the folding blade solenoids 80 and 142 are somewhat different and may be described as follows.

- A small sheet on the right hand side of the machine at its forward edge interrupts the beam of light from the photoelectric cell 604. This photoelectric cell is connected by a cable 712 to an amplifier-relay 714 which closes its switch 716 upon a decrease in light on the photoelectric cell 604. The switch 716 completes the circuit from the supply line L-1 through the wire 718, the wire 720, and the wire 722 to the solenoid 124 and from the solenoid 124 through the wire 726, the switch 716, the wire 728, the wire 730, and the wire 700 to the supply line L-2. Power is supplied to the amplifier-relay through the wires 720 and 730. The switch 732 controlled by the relay 724 completes a circuit to the clutch control solenoid 544 from the supply line L-1, through the wire 718, the wire 734, the lower arm of the switch 732, the wire 736, the solenoid 544, the wire 738, the upper arm of the switch 732, the wire 740 and the wire 700 to the supply line L-2. The solenoid 544 releases the clutch 510 for operation through a predetermined number of revolutions to effect movement of the mirrors 216 and 218. When the mirror 216 (or the mirror 218) passes from beneath the rear edge of the sheet, a beam of light from the source 234 is directed into the photoelectric cell 236.
- 30 The luminous source or lamp 234 and the lamp 164 are connected in parallel in a circuit controlled by the two upper and normally closed contacts of the switch 696. This circuit is completed from the supply line L-1 through the wire 718, the wire 742, the upper arm of the switch 696, the wire 744, the lamps 234 and 164 in parallel, the wire 694, the second arm of the switch 696, the wire 698 and the wire 700 to the supply line L-2.
- 40 When light is directed into the photoelectric cell 236 as one of the measuring mirrors of the photoelectric measuring unit 18 passes from beneath the rear edge of the sheet, the switch 748 is moved to closed position by the amplifier-relay 45 750 which is connected to the photoelectric cell 236 by the cable 752. The switch 748 when closed completes a circuit from the line L-1 through the wire 718, the wire 754, a relay 756, the wire 758, the switch 748, the wire 760, the wire 762 and the wire 700 to the line L-2. The amplifier-relay receives its power through the wires 754 and 762. The switch 764 operated by the relay 756 energizes the first folding blade solenoid 80 through a circuit completed from the line L-1 through the wire 718, the wire 766, the solenoid 80, the wire 768, the lower arm of the switch 764, the wire 770, and the wire 700 to the line L-2. Simultaneously with the energization of the solenoid 80, a circuit is completed through 55 the clutch control solenoid 424 to initiate operation of the timing chain 422 of the measuring and timing means 24. This circuit is completed from the line L-1 through the wire 718, the wire 772, the solenoid 424, the wire 774, the switch 776, the wire 778, the upper arm of the switch 764, the wire 780 and the wire 700 to the line L-2. The timing chain 422 by means of its lugs similar to the lugs 338 and 340 operates the travelling second fold control switch 428 when the once-folded sheet is properly positioned for the effecting of the second fold. The switch 428 completes a circuit from the line L-1 through the wire 782, the relay 784, the wire 786, the switch 428, the wire 788, the second and normally closed arm of the switch 696, the wire 698 and the wire 75

700 to the line L—2. The relay 184 operates its switch 790 to complete a circuit to the second folding blade solenoid 142, this circuit extending from the line L—1 through the wire 718, the wire 792, the solenoid 142, the wire 794, the switch 790 and the wire 796 to the line L—2.

The switch 776, as well as the switch 680, may comprise manually operable switches placed as shown in Fig. 1 on opposite sides of the machine in convenient position to be manipulated by operators at the platform 60 so as to break the circuits to the clutch control solenoids 272 and 424 and thereby by-pass once-folded sheets by disabling the second fold-forming mechanism. It will be evident of course that these switches may be selectively operated so that small articles on one side of the machine may be automatically folded twice while small articles on the other side are only folded once. A reset switch 798 mounted on the left hand frame member 36 is connected in shunt with the upper arm of the switch 668 by means of the wires 800, 802, 638 and 684, thus providing manual means for completing the circuit to the solenoid 272 independently of the switch 668 whereby to effect a resetting operation of the measuring and timing means 22 if such should be necessary. A similar manually operated resetting switch 804 is mounted on the right frame member 36, Fig. 1, and is connected to the solenoid 424 in shunt to the upper arm of the switch 764 through the wire 718, wire 806, the wire 808, the wire 700, and the wire 780 so that this solenoid 424 may be energized independently of the switch 764 to effect a resetting operation of the measuring and timing means 24 if such should be necessary. The resetting switches 798 and 804 may be connected for simultaneous operation, as shown in Figs. 1 to 4 and 8, by means of a bar 810 mounted in suitable brackets upstanding from the side frame members and connected at each end to a switch operating arm 812 by means of a crank 814 and a link 816, the switch operating arm 812 being pivoted to a suitable bracket 818. The rod 810 is oscillated to effect operation of the resetting switches 798 and 804 by means of a board or panel 819 extending transversely substantially the full width of the machine so that it may be conveniently operated in any position between the side frames, the panel 819 being secured to the rod 810 as by arms 820 secured at their upper ends to the rod.

Operation of the machine to fold large articles

For the purposes of this description, large articles or sheets are considered to be those which extend from the left side of the machine to the center thereof so as to pass beneath the light sources 438 and 462 and the left and centrally positioned lamps 616.

When a large article, indicated by the numeral 822 in Fig. 26, reaches the position there shown, at which it interrupts the light beam projected upon the photoelectric cell 602, the mirrors 446, 472 and 474 occupy their normal rest positions as shown in this figure. The photoelectric cell 602 is connected by a cable 824 to an amplifier-relay 826 which closes its switch 828 upon a decrease in light on the photoelectric cell 602. Therefore, when the forward edge of the sheet interrupts the light from the photoelectric cell 602 the switch 828 completes a circuit from the supply line L—1 through the wire 718, the wire 830, the wire 832, the relay 834, the wire 836, the switch 828, the wire 838, the wire 840 and the wire 700.

5 to the supply line L—2. The relay 834 operates the switch 696 to complete a circuit for the luminous sources 438 and 462; to break the circuit to the luminous sources 164 and 234, and to break the circuits to the solenoids 688 and 784. The circuit for the luminous sources 438 and 462 is completed from the line L—1 through the wire 718, the wire 742, the third arm of the switch 696, the wire 842, the lamps 438 and 462 in parallel, the wire 844, the fourth arm of the switch 696, the wire 698, and the wire 700 to the line L—2. The circuit to the lamps 164 and 234 which are in parallel and energized through the wires 694 and 744 is broken at the first and second arms of the switch 696. The circuit to the relays 688 and 784 are broken at the second arm of this switch 696. The breaking of these relay circuits prevents operation of the second folding blades by the second fold control switches 298 and 428 so long as there is a sheet passing over the photoelectric cell 602. When a large sheet at its forward edge interrupts the beam of light to the photoelectric cell 602, it also interrupts the beam of light to the photoelectric cell 600. The photoelectric cell 600 by means of the amplifier-relay 624 closes the switch 626 to complete the circuit as previously described to the relay 628. The switch 646 operated by the relay 628 completes the circuit to the clutch control solenoid 540 which therefore initiates operation of the photoelectric measuring unit 16 but, since the sheet is large, the mirrors of this unit complete one movement without effect. The switch 646 also completes a circuit to the clutch control solenoid 542 for the photoelectric measuring unit 20. This circuit is completed from the line L—1 through the wire 636, the wire 644, the fourth arm of the switch 646, the wire 846, solenoid 542, wire 848, the third arm of the switch 646, the wire 652 and the wire 638 to the line L—2. Solenoid 542 initiates operation of the clutch 508 which thereupon drives the chains 450 through a complete movement to move the mirror 446 from the position shown in Fig. 26 through a complete cycle back to this same original position. As this mirror 446 passes out from under the rear edge of the sheet 822 as shown in Fig. 27, it directs a beam of light from the source 438 into the photoelectric cell 448. The photoelectric cell 448 is connected to an amplifier-relay 850 by a cable 852 and the amplifier-relay 850, upon an increase in light on the photoelectric cell, closes its switch 854. The switch 854 completes a circuit from the power leads 660 and 664 through the relay 856. The relay 856 simultaneously completes circuits to energize both first folding blade solenoids 78 and 80 and to energize the clutch control solenoid 272. The circuit to the folding blade solenoid 78 is completed from line L—1 through the wire 636, the wire 666, the second arm of the switch 858, the wire 860, the wire 672, the solenoid 78, the wire 674 and the wire 638 to the line L—2. The circuit to the folding blade solenoid 80 is completed from the line L—1 through the wire 718, the wire 766, the solenoid 80, the wire 768, the wire 862, the third arm of the switch 858, the wire 684 and the wire 638 to the line L—2. The circuit to the clutch control solenoid 272 is completed from the line L—1 through the wire 636, the wire 676, the solenoid 272, the wire 678, the now-closed cut-out switch 680, the wire 682, the wire 800, the wire 864, the top arm of the switch 858, the wire 684, and the wire 638 to the line L—2.

60 The solenoid 272 now releases the clutch 274 which drives the chain 276 and this chain in turn

through the shaft 192 drives the chains 466 of the photoelectric measuring unit 26. The mirrors 472 and 474 start to move from their initial and normal rest position as shown in Fig. 27 in a clockwise direction until mirror 474 reaches the position shown in Fig. 28 and passes from beneath the rear edge of the now once-folded sheet 822. The mirror 474 directs a beam of light from the source 452 upon the photoelectric cell 476. The photoelectric cell 476 is connected by a cable 866 to an amplifier-relay 868 which moves its switch 870 to circuit closing position upon an increase in light on the photoelectric cell. The switch 870 completes a circuit from the line L-1 through the wire 636, the wire 634, the switch 870, the wire 872, the relay 874, the wire 876, the wire 640, and the wire 638 to the line L-2. This results in the energization of the relay 874 and the closing of the switch 878. The switch 878 completes the energizing circuits for the second folding blade solenoids 140 and 142. The circuit to the solenoid 140 is completed from the line L-1 through the wire 636, the wire 880, the lower arm of the switch 878, the wire 882, the wire 706, the solenoid 140, the wire 708, and the wire 638 to the line L-2. The circuit for the solenoid 142 is completed from the line L-1 through the wire 718, the wire 792, the solenoid 142, the wire 794, the wire 884, the upper arm of the switch 878, the wire 886, and the wire 638 to the line L-2. The second folding blade sections 128 and 130 therefore operate simultaneously to effect the second fold of large articles.

The mirror 446 in effecting a measuring operation moves a distance substantially equal to one-half the length of the sheet, while the measuring mirror 472 or 474 moves through a distance substantially equal to one-fourth the length of the sheet plus a distance equal to the distance of movement of the sheet between the first and second folding blades. Theoretically, the mirror 446 should travel a distance exactly equal to one-half the length of the sheet. However, in actual practice, this mirror is, in normal rest positions, advanced on the chains 450 a slight distance to compensate or make allowance for the operating interval required between the exciting of the photoelectric cell 448 and the actual engagement of the first folding blades with the sheet, the mirror 446 passing out from beneath the rear edge of the sheet just prior to the time that the center of the sheet is above the folding blade so that by the time the folding blade actually engages the sheet, the center will have been moved forwardly by the conveying tapes and be squarely positioned over the folding blade.

For similar reasons, each of the mirrors 472 and 474 is advanced on the chains 466 with respect to their theoretical rest positions so that the active mirror passes out from under the rear edge of the once-folded sheet sufficiently in advance of the time that the center of the once-folded sheet reaches the second folding blades as to allow the folding blades to be moved into actual engagement with the sheet at precisely the same instant that the center of the once-folded sheet is above the folding blades.

A by-pass switch 888, Fig. 32, which may be located in any desired position, as for example, at the feeding in end of the ironing machine 58, or at the delivery end of the folding machine 2, is inserted in one or both of the supply lines and when manually moved to open position renders the control circuits ineffective so that articles may be by-passed through the folding machine

without being folded where the articles are of such a nature that they should not be folded. In some cases, it may be found advantageous to have the photoelectric measuring unit 20 controlled solely by the photoelectric cell 602 rather than by both photoelectric cells 600 and 602, as for example where long but unusually narrow sheets are frequently encountered or where for other reasons it may be found advantageous to fold large sheets without regard to the placement of the sheet relative to the photoelectric cell 600. In such case the control circuit may be modified as shown in Fig. 33 which modification, however, may, for these reasons, be preferred in many installations. As shown in Fig. 33, the lamps or luminous sources 164, 234, 438 and 462 are connected in parallel to the lamps 616 so that all of the lamps or light sources are continuously energized. The lamp 164 is connected to the supply leads 700 and 718 for the lamp 616 by the cable 890. Similarly, the lamps 234, 438 and 462 are connected to the supply leads 700 and 718 by the cables 892, 894 and 896. The clutch controlled solenoid 542 which determines the operation of the measuring unit 20 is connected by the cable 898 to the two lower and normally opened contacts of the switch 696 which is controlled by the relay 834 that is in turn energized in response to the interruption of the light upon the photoelectric cell 602. In other respects, the circuit is substantially identical to the circuit shown in Fig. 32. It should be noted, however, that the connections between lamps 164, 234, 438 and 462 and the switch 696 shown in Fig. 32 are eliminated as are also the connections between the clutch control solenoid 542 and the switch 646.

It will be seen from the foregoing description that applicant has provided a machine for folding flatwork articles of laundry wherein relatively simple control mechanisms are provided which are responsive to the presence of an article or sheet to be folded to measure the article or sheet and effect a folding thereof along one or more predetermined lines of fold proportioned in accordance with the length of the article or sheet and which mechanism does not include any means, device or element which by physical contact with the article might tear or otherwise injure the article. It will also be apparent that the several measuring means or units are inherently maintained in synchronism with the movement of the feed tapes and at the same time are rugged in structure and are well adapted for the performance of their several functions.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. In a machine for automatically folding articles of different lengths and having a machine frame, article conveying means, folding mechanism, measuring means movable upon each operation a fixed distance at a single speed proportional to the speed of the article conveying means along a given path in spaced relation to the article being conveyed, means operatively controlled by an article for initiating operation of said measuring means when the article reaches a predetermined position relative to said measuring means, automatic means for terminating oper-

ation of said measuring means when moved said fixed distance, and means including a control element stationary with respect to the machine frame and cooperatively controlled by said measuring means and said article upon completion of the measurement of the article by said measuring means and irrespective of the distance moved by said measuring means for operating said folding mechanism thereby to fold articles of different length in portions predetermined by their measurements.

2. In a folding device, a folding mechanism, a traveling article measuring means, means including a control element operatively controlled by the article for causing said measuring means to be moved oppositely to the article along a fixed path in spaced, non-contacting relation to the article at a single speed substantially equal to the speed of movement of the article, and means including a second control element independent of the first control element and conjointly controlled by the article and said measuring means for operating said folding mechanism immediately upon completion of the measurement of the article by said measuring means.

3. In a folding device, a folding mechanism, a traveling article measuring means, means independent of the folding mechanism for driving said article measuring means through a given cycle of movement in spaced relation to the article for each operation thereof, means operatively controlled by the article for initiating operation of said driving means, and means operatively controlled by said measuring means for immediately actuating said folding mechanism upon completing the measurement of said article and irrespective of the position of said measuring means in its cycle of movement.

4. In a folding device, folding mechanism, article measuring means, means for driving said article measuring means a fixed distance for each operation of the driving means, means operatively controlled by one edge of the article for initiating operation of said driving means, means independent of said operation initiating means and conjointly controlled by the article and said measuring means for immediately actuating said folding mechanism when said measuring means passes an opposite edge of the article upon completion of the measuring operation.

5. In a folding machine having a stationary frame, folding mechanism, means for operating said folding mechanism including a ray source, ray controlling means movable along a fixed path in spaced relation to the article to measure said article, means operatively controlled by the article for initiating operation of said measuring means, ray-sensitive means stationary with respect to the frame and operably energized by said ray source under the control of said ray controlling measuring means and means operatively controlled by said ray-sensitive means and operatively connected to said folding mechanism to fold the article upon the completion of the measuring operation.

6. In a folding machine having a stationary frame, a folding mechanism, a traveling article measuring means, ray-sensitive means stationary with respect to the frame and operatively controlled by the article for causing said measuring means to be moved along a fixed path in spaced relation to the article, and means independent of said ray-sensitive means and operatively controlled by said measuring means for operating said folding mechanism.

7. In a folding machine having a stationary frame, the combination of a folder, means for moving articles toward the folder, means for measuring articles, means including a control element stationary with respect to the frame and operatively controlled by the forward end of an article for moving said measuring means oppositely toward the rear end of the article, and means independent of said stationary control element and operatively controlled by said measuring means when said measuring means reaches a position in predetermined relation to the rear end of the article for actuating said folder.

8. In a folding machine having a stationary frame, folding mechanism, ray sensitive means stationary with respect to the frame for controlling said folding mechanism, a ray source and traveling ray directing measuring means operatively controlling the direction of rays from said source to said ray sensitive means.

9. In a folding machine having a stationary frame, folding mechanism, a ray source, ray directing means movable along a fixed path in spaced relation to the article to measure said article, means operatively controlled by the article being conveyed for driving said ray directing means, and ray sensitive means stationary with respect to the frame and receiving rays from said ray directing means upon the completion of the measuring operation for operating said folding mechanism.

10. In a folding machine having a stationary frame, folding mechanism, a ray source stationary with respect to the frame, ray directing means movable along a fixed path in spaced relation to the article to measure said article, ray sensitive means operatively controlled by the article being conveyed for initiating movement of said ray directing means, and a second ray sensitive means receiving rays from said source directed by said ray directing means upon the second ray sensitive means on the completion of the measuring operation for operating said folding mechanism.

11. In a folding device, a first folding mechanism, a second folding mechanism receiving the once folded article from the first folding mechanism for effecting a second fold of the article, means movable along a fixed path in spaced, non-contacting relation to the article to measure said article, means operatively controlled by the article for initiating the operation of said measuring means, timing means for operating said second folding mechanism a given interval after the operation of the first folding mechanism and when the once folded article is in proper position relative to the second folding mechanism and means conjointly controlled by the article and said measuring means for operating the first folding mechanism and initiating the operation of said timing means upon completion of the measuring operation.

12. In a folding machine having a stationary frame, folding mechanism, means for conveying articles to the folding mechanism, a light source, light sensitive means stationary with respect to the frame and operatively controlling said folding mechanism, movable light directing means, means for driving said light directing means at a speed proportioned to the speed at which the article is moved by said conveying means, and means for initiating operation of said driving means when an edge of an article is in a predetermined position relative to the folding mechanism, said light directing means being driven by said driving

means in a direction toward an opposite edge of the article and when in a given relative position to said opposite edge directing a beam of light from said source upon the stationary light sensitive means, thereby to effect the folding of the article in accordance with the length thereof.

13. In a folding machine, first and second folding mechanisms, light sensitive means for actuating the first folding mechanism, means for measuring the length of an article to be folded and controlling the light upon the light sensitive means in accordance with the measured length of the article thereby to effect the first fold of the article, a traveling switch operable in synchronism with said measuring means during its measuring operation, and timing means operatively controlled by said light sensitive means for operating said traveling switch when the once folded article is in folding relation to the second folding mechanism.

14. In a folding machine, a first conveyor for articles to be folded, folding mechanism for folding an article on said conveyor, light sensitive means for actuating said folding mechanism, a light source, and movable light directing means positioned on opposite sides of the article-carrying surface of the conveyor to permit the article to pass between said source and said light directing means, a second conveyor for moving said light directing means oppositely to the direction of movement of the article, means for driving said article conveyor and said second conveyor at predetermined relative speeds in opposite directions, a second folding mechanism, a third conveyor for conveying the once folded article from said first folding mechanism to said second folding mechanism, electrically operable means for actuating said second folding mechanism, a traveling switch for controlling said electrically operable means, a fourth conveyor operatively connected to said driving means and driven thereby at the same speed as the light directing means, means for releasably connecting said traveling switch to said last mentioned conveyor for movement in one direction in synchronism with the light directing means, means operatively controlled by said light sensitive means for releasing said traveling switch from the fourth conveyor upon completion of the measuring operation of said light directing means, means operatively controlled by the light sensitive means for moving said traveling switch in the opposite direction upon release from the fourth conveyor and at a speed proportioned to the speed of movement of the third article conveyor, means movable oppositely to the released traveling switch and at an equal speed for operating said traveling switch thereby to actuate the second folding mechanism.

15. In a folding machine, a first conveyor for articles to be folded, folding mechanism for folding an article on said conveyor, light sensitive means for actuating said folding mechanism, a light source, and movable light directing means positioned on opposite sides of the article-carrying surface of the conveyor to permit the article to pass between said source and said light directing means, a second conveyor for moving said light directing means oppositely to the direction of movement of the article, means for driving said article conveyor and said second conveyor at predetermined relative speeds in opposite directions, a second folding mechanism, a third conveyor for conveying the once folded article from said first folding mechanism to said second folding mecha-

nism, electrically operable means for actuating said second folding mechanism, a traveling switch for controlling said electrically operable means, a fourth conveyor operatively connected to said driving means and driven thereby at the same speed as the light directing means, means for releasably connecting said traveling switch to said last mentioned conveyor for movement in one direction in synchronism with the light directing means, means operatively controlled by said light sensitive means for releasing said traveling switch from the fourth conveyor upon completion of the measuring operation of said light directing means, means operatively controlled by the light sensitive means for moving said traveling switch in the opposite direction upon release from the fourth conveyor and at a speed proportioned to the speed of movement of the third article conveyor, switch operating means, means operatively controlled by the light sensitive means for connecting said switch operating means to said moving means for movement oppositely to the released traveling switch and at equal speed thereby to actuate the second folding mechanism when the once folded article is in folding relation to the second folding mechanism.

16. In a folding machine, first and second folding mechanisms each comprising a plurality of aligned folding blades, light control means operatively controlled by a large article to be folded for simultaneously actuating the folding blades of the first folding mechanism, light control means operatively controlled by the once folded article for simultaneously actuating the folding blades of the second folding mechanism to effect the second fold of the large article, a plurality of light control means operatively controlled by small articles to be folded for selectively actuating the folding blades of the first folding mechanism, and a plurality of timing means operatively controlled by said plurality of light control means for small articles for selectively actuating the folding blades of the second folding mechanism.

17. In a folding machine, first and second folding mechanisms each comprising a plurality of aligned folding blades, light control means operatively controlled by a large article to be folded for simultaneously actuating the folding blades of the first folding mechanism, light control means operatively controlled by the once folded article for simultaneously actuating the folding blades of the second folding mechanism to effect the second fold of the large article, a plurality of light control means operatively controlled by small articles to be folded for selectively actuating the folding blades of the first folding mechanism, a plurality of timing means operatively controlled by said plurality of light control means for small articles for selectively actuating the folding blades of the second folding mechanism, means operatively controlled by a large article for initiating operation of the first light control means for large articles, and means operatively associated with each of the plurality of light control means for small articles and operatively controlled by a small article in operative relation to one of these light control means for initiating operation of that operatively related light control means.

18. In a folding machine, first and second folding mechanisms each comprising a plurality of aligned folding blades, light control means operatively controlled by a large article to be folded for simultaneously actuating the folding blades

of the first folding mechanism, light control means operatively controlled by the once folded article for simultaneously actuating the folding blades of the second folding mechanism to effect the second fold of the large article, a plurality of light control means operatively controlled by small articles to be folded for selectively actuating the folding blades of the first folding mechanism, a plurality of timing means operatively controlled by said plurality of light control means for small articles for selectively actuating the folding blades of the second folding mechanism, means normally rendering ineffective the light control means for large articles, and means operatively controlled by a large article for rendering effective said light control means for large articles and for rendering ineffective the light control means for small articles.

19. In a folding machine, folding mechanism comprising a pair of aligned folding blades, light control means operatively controlled by a large article to be folded for simultaneously actuating said folding blades, a plurality of light control means operatively controlled by small articles to be folded for selectively actuating said folding blades, and means operatively controlled by the articles for selectively rendering ineffective the light control means for large articles and the light control means for small articles.

20. In a folding device, a folding mechanism, traveling article measuring means operatively controlling said folding mechanism, driving mechanism, means for connecting said article measuring means to said driving mechanism, means operated by the articles for controlling said connecting means to connect said article measuring means to said driving mechanism, and means for operating said connecting means to release said article measuring means from said driving mechanism even though said controlling means is held operated by an article.

21. In a folding device, folding mechanism, a conveyor for successively conveying articles to said folding mechanism, traveling article measuring means, driving mechanism, a clutch adapted to connect said driving mechanism to said article measuring means, clutch control means, means controlled by the articles for operating said clutch control means to render the clutch effective to connect said article measuring means to said driving mechanism, said operating means including quick re-set means for releasing said clutch control means even though said control means remains under the control of an article, and means for maintaining said control means in operative position wherein the clutch connects the driving mechanism to the article measuring means during movement of the article measuring means through a fixed distance.

22. In a folding machine having a stationary frame, article conveying means, folding mechanism, ray-sensitive means stationary with respect to the frame for controlling said folding mechanism, means providing a ray beam elongated in the direction of conveyance of the article and extending from one side across the path of the article, measuring mechanism including ray directing means movable along a path at least a portion of which extends parallel with the elongated ray beam on the opposite side of the article path, means for initiating movement of said ray directing means when the article is in a given position, said stationary ray-sensitive means being disposed relative to the path of the ray directing means to receive the beam there-

from upon completion of the measuring operation when the article occupies a given position relative to the folding mechanism.

23. In a folding machine having a stationary frame, folding mechanism, article conveying means carrying articles to the folding mechanism, ray-sensitive means stationary with respect to the frame for controlling said folding mechanism, means providing an elongated ray beam extending from one side across the path of conveyance of the articles, and traveling ray-directing measuring means on the opposite side of the path of conveyance of the articles and operatively controlling said stationary ray-sensitive means.

24. In a folding device, folding mechanism, a ray source, ray-directing means movable along a fixed path in spaced relation to the article to measure said article, stationary ray-sensitive means operatively controlled by said ray-directing measuring means for operating said folding mechanism and means focussing only the beam received from said ray-directing means upon the ray-sensitive means.

25. In a folding machine, article conveying means, first and second folding mechanisms spaced along the path of conveyance of the articles, ray-sensitive means for actuating the first folding mechanism, ray-sensitive means for actuating the second folding mechanism, means providing a ray beam extending from one side across the path of conveyance of the article and elongated in the direction of conveyance of the article, measuring mechanism including ray-directing measuring means movable along a path at least a portion of which extends parallel to the path of conveyance of the articles on the opposite side of said path of conveyance of the article, means for driving said ray-directing means along said portion of the path in a direction opposite to the direction of conveyance of the articles at a speed proportionate to the speed of conveyance of the articles, the first ray-sensitive means being disposed to receive the beam from said ray-directing means upon completion of the measuring operation and actuating the first folding mechanism to fold the article in proportionate parts, means providing a second ray beam also extending from one side across the path of conveyance of the articles, mechanism for measuring the once-folded article, said last-mentioned mechanism including a second ray-directing means movable along a path at least a portion of which extends parallel to the path of conveyance of the article on the opposite side of said path, means operatively controlled by the first ray-sensitive means for driving said second ray-directing means at a speed equal to the speed of conveyance of the once-folded article, the second ray-sensitive means being disposed to receive the ray beam from said second ray-directing means upon completion of the measuring operation and actuating the second folding mechanism to fold the once-folded article in half.

26. In a folding machine, article conveying means, first and second folding mechanisms spaced along the path of conveyance of the articles, traveling ray-directing measuring means movable in spaced non-contacting relation to the article to measure said article, ray-sensitive actuating means controlled by said measuring means and including means for operating said first folding mechanism, and a timer set into operation by said measuring means for actuating the second folding mechanism a given interval

after the completion of the measuring operation and when the article is in proper position relative to the second folding mechanism.

27. In a folding machine, first and second folding mechanisms, a first ray-sensitive means for actuating the first folding mechanism, a second ray-sensitive means for actuating the second folding mechanism, means for measuring the article to be folded, said measuring means including a device cooperating with the article to control the first ray-sensitive means whereby to actuate the first folding mechanism upon completion of the measurement of the article to be folded, means operatively controlled by the first ray-sensitive means for measuring the once-folded article, said last-mentioned measuring means comprising ray-controlling means cooperating with the article to control the second ray-sensitive means whereby to actuate the second folding mechanism upon completion of the measurement of the once-folded article.

28. In a folding machine, first and second folding mechanisms, ray-sensitive means for actuating the first folding mechanism, means for measuring the length of an article to be folded, said measuring means comprising means for controlling the direction of rays to the ray-sensitive means to effect the first folding of the article upon completion of the measuring operation, a traveling switch for actuating said second folding mechanism, means for driving said traveling switch, means for operating said traveling switch, means for driving said switch operating means in a direction opposite to said traveling switch, means for simultaneously initiating operation of said traveling switch driving means and said measuring means, and means controlled by the ray-sensitive means for initiating operation of the driving means for the switch operating means upon completion of the measuring operation.

29. In a folding machine having a stationary frame, an article conveyor, a folding blade swinging across the path of movement of the conveyed article to fold said article, a solenoid for operating said folding blade, a stationary light-sensitive device controlling the energization of said solenoid, means including a light source stationary with respect to the frame, and a traveling light-directing measuring means for controlling the projection of light upon said light-sensitive means to actuate said solenoid in accordance with the measurement of the article.

30. In a folding device, a folding mechanism, means for conveying the article to be folded to the folding mechanism, a ray source and traveling ray-reflecting measuring means disposed on opposite sides of the path of movement of the article as it is conveyed to the folding mechanism, means controlled by the article for initiating operation of said measuring means, and stationary ray-sensitive means receiving rays from said source under the control of said ray-reflecting measuring means and operatively connected to the folding mechanism for actuating said folding mechanism to fold the article into portions predetermined by the measurement of the article by the ray-reflecting measuring means.

31. In a folding machine having a stationary frame, a folding mechanism, means for conveying the article to said folding mechanism, a traveling article measuring means movable in spaced non-contacting relation to the article, means adapted to drive said article measuring means oppositely to the article being conveyed

and synchronously therewith, a normally released clutch for connecting said driving means to said article measuring means, means controlled by the article for operating said clutch

5 to connect the article measuring means to the driving means, said traveling article measuring means including a ray-directing device, and ray-sensitive means stationary with respect to the frame and conjointly controlled by the article 10 and said ray-directing device for actuating said folding mechanism to fold the article into portions predetermined by the measurement thereof.

32. In a folding machine, means for conveying relatively small articles along parallel lanes 15 and large articles which extend from one lane to another, a plurality of aligned folding devices, one for each of said lanes and extending transversely of the path of conveyance of articles along said lane, a plurality of traveling article

20 measuring means including one for each of said lanes for measuring small articles, driving means for each of said article measuring means for moving its associated article measuring means along a fixed path in spaced non-contacting relation to the article being conveyed, a plurality of actuating devices each operatively controlled by one of said small article measuring means to individually actuate its associated folding device, traveling article measuring means for measuring

25 large articles extending from one lane to another, and means controlled by said large article measuring means for simultaneously operating the actuating means for adjacent lanes along 30 which the large articles are being conveyed, 35 whereby simultaneously to operate the adjacent folding devices.

33. In a folding machine, means for conveying relatively small articles along parallel lanes and large articles which extend from one lane to another, a plurality of aligned folding devices, one for each of said lanes and extending transversely of the path of conveyance of articles along said lane, a plurality of traveling article

40 measuring means including one for each of said lanes for measuring small articles, driving means for each of said article measuring means for moving its associated article measuring means along a fixed path in spaced non-contacting relation to the article being conveyed, a plurality of actuating devices each operatively controlled by one of said small article measuring means to individually actuate its associated folding device, traveling article measuring means for measuring

45 large articles extending from one lane to another, means controlled by said large article measuring means for simultaneously operating the actuating means for adjacent lanes along 50 which the large articles are being conveyed, whereby simultaneously to operate the adjacent folding devices, and means controlled by large articles for preventing operation of the actuating means by the small article measuring means.

55 34. In a folding device, a first folding mechanism, a second folding mechanism spaced from the first folding mechanism for receiving articles to be folded from the first folding mechanism, means for conveying articles to the first folding mechanism and then to the second folding mechanism, means actuating said first folding mechanism, article measuring mechanism including means operatively controlling said actuating means to effect the first folding of the article upon completion of the measuring operation, means actuating the second folding mechanism, means preset by said article measuring

60 70 75

mechanism in accordance with the measurement of the article for subsequent actuation of the actuating means for the second folding mechanism, and timing means set into operation by the first fold actuating means for subsequently operating said preset means to effect actuation

of the actuating means for the second folding mechanism when the article has traversed the space between said folding mechanisms and is in folding relation to the second folding mechanism.
